UNITED STATES PATENT OFFICE.

WAYNE J. HULL, OF ALEXANDRIA, DAKOTA TERRITORY, AND WILLIAM E. VARNEY, OF DAYTONVILLE, IOWA.

SCROLL-SAWING MACHINE.

SPECIFICATION forming part of Letters Patent No. 296,693, dated April 8, 1884.

Application filed January 29, 1884. (No model.)

To all whom it may concern:

Be it known that we, WAYNE J. HULL, residing at Alexandria, in the county of Hanson and Territory of Dakota, and WILLIAM E. VARNEY, residing at Daytonville, in the county of Washington, State of Iowa, citizens of the United States, have invented certain new and useful Improvements in Wood-Working Machines; and we do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of an end view of my machine. Fig. 2 is a side view of the same. Fig. 3 is a transverse sectional view, and Fig. 4 is a plan view of the table.

This invention has relation to wood-working machines; and it consists in the construction and arrangement of parts, as will be herein-after fully described, and particularly pointed out in the claims appended.

Referring by letter to the accompanying drawings, A designates the bench or bed frame, which is of ordinary construction, longitudinally slotted and flanged to receive the adjustable and removable mechanism usually employed. An ordinary treadle or steam power may be used to drive the machinery.

The main mandrel, auxiliary mandrel, clutch mechanism, and driving mechanism are the same as those portions of the machine as described in our Letters Patent No. 279,051, of June 5, 1883, wood-working machines, and are not broadly claimed herein. Reference is, however, made to said patent for a detailed description of said parts, which are partly shown herein.

B³ designates a frame which is clamped to the bed-frame A, and is adapted to slide thereon when the clamp is loosened.

To use the scroll-saw with the driving mechanism, the frame B³, carrying the table B⁴, should be moved up until a crank-shaft, B⁵, (which is threaded on its outer end,) engages the internally-threaded portion of the main

shaft D, the driving mechanism being operated to draw the male into the female screw, thus forming a connection between the main shaft D and the crank-shaft B⁵. This crank-shaft B⁵ has one of its bearings in the left-hand end E² of the frame B³. F⁵ designates the right-hand end of the frame B³. The left-hand end E² of the frame B³ has secured to its left face vertical ways H³, in which reciprocates a bifurcated arm, H⁴, which is provided at the upper end of its bifurcation with a clamping-nut, H⁵, for holding the lower end of the scroll-saw H⁶, which works vertically. The lower portion of this bifurcated arm H⁴ passes through a bearing or guide, H⁷, and its lower end is rigidly secured to a wrist-pin, I², upon which the lower end of a pitman-rod, I³, articulates, the upper end of which is removably clamped by a hinge-clamp, I⁴, held in place by a set-screw to the horizontal portion of a double crank, I⁵, upon the crank-shaft B⁵. A circular metallic guard-plate, J¹, having a central perforation and a radial groove, J², arranged in the lateral line of the table B⁴, is let into the surface of said table, and is provided with an adjustable slide, J³, having at its inner end vertical recesses, in which the back of the saw plays.

K' designates an arm, the base of which is secured to the right-hand end of the bench-frame A, and has a locking-pin, K², passed through a perforation therein and into an aligned perforation in the end of the bench-frame, to prevent it from accidentally turning out of place, but which, when designedly removed, will permit said arm to be turned out of place when disconnected from the upper end of the scroll-saw. The free end of this arm K' is provided with vertical ways K³, in which a slotted slide, K⁴, adjustably connected to a spring-arm, L², upon the arm K', works. The lower end of said vertical slotted slide K⁴ is provided at its lower end with a vertical recess, L³, to receive the upper end of the saw-blade, and a downwardly and inwardly incline, L⁴, to receive the cross-pin L⁵, by which the saw is removably connected to the said blade.

In the vertical slot M² is provided a bolt, M³, having a washer and a securing-nut, by

which it may be adjusted to any point within said slot for the purpose of adjusting it to saws of different lengths.

The rear side of the vertical ways K³ is provided with a vertically-perforated bearing, N³, in which a vertical rod, N⁴, is adapted to be adjusted vertically. The lower end of this rod N⁴ is provided with an adjustable bifurcated foot, N⁵, secured in place by a nut and washer upon its under face. Its solid end is provided with a vertical recess, in which the back of the scroll-saw plays when in operation. It may be adjusted back and forth to suit saws of different widths, and serves both as a guide and a brace for the same.

Having thus fully described our invention, what we claim as new, and desire to secure by Letters Patent, is—

1. In a wood-working machine, the combination of the arm K', provided at its free end with the vertical ways K³, and the slotted slide K⁴, adjustably connected to the spring-arm L², the slide K⁴ being provided with the lateral recess L¹, intersected by the vertical recess L², the latter to receive the upper end of the saw-blade and the former to receive the cross-pin L⁵, by which the saw is removably connected to the slide K⁴, substantially as specified.

2. In a wood-working machine, the combination, with the frame B³, carrying the table B⁴, of the circular metallic guard-plate J',

having a central perforation and a radial groove, J², arranged in the lateral line of the table B⁴, let into the table, and provided with an adjustable slide, J³, having its inner end recessed vertically, and the scroll-saw and mechanism for operating the same, substantially as specified.

3. In a wood-working machine, the combination, with the frame B³ on the bench-frame A, and table B⁴, located thereon, of the bifurcated arm H⁴, arranged beneath the table, having the clamping-nut H⁵ at its upper end, crank I⁵, clamp I⁴, the crank-shaft B⁵, having end bearings in the frame B³ and shaft D, pitman-rod I³, connected at its upper end to the said crank, the arm K', rising from the frame, and provided with a spring-arm, L², the vertically-slotted slide K⁴, the adjustable bifurcated foot N⁵, and operating mechanism, substantially as specified.

In testimony whereof I affix my signature in presence of two witnesses.
